UNITED STATES PATENT OFFICE

171,201

COMBINATION CABINET AND EASEL

Lester L. Fisher, Lansdale, Pa., assignor to American-Olean Tile Company, Lansdale, Pa., a corporation of Pennsylvania

Application June 8, 1953, Serial No. 25,373

Term of patent 14 years

(Cl. D33—19)

To all whom it may concern:

Be it known that I, Lester L. Fisher, a citizen of the United States, residing in Lansdale, Montgomery County, Pennsylvania, have invented a new, original Design for a Combination Cabinet and Easel, of which the following is a specification, reference being had to the accompanying drawing, forming a part hereof.

Fig. 1 is a front elevational view of a combination cabinet and easel, showing my new design;

Fig. 2 is a side elevational view of the combination cabinet and easel shown in Fig. 1;

Fig. 3 is a rear elevational view of the combination cabinet and easel;

Fig. 4 is a front view in perspective of the combination cabinet and easel, and

Fig. 5 is a rear view in perspective of the combination cabinet and easel.

I claim:

The ornamental design for a combination cabinet and easel, substantially as shown.

LESTER L. FISHER.
